Primary Examiner — Messina L Smith*Assistant Examiner* — Elizabeth Borsetti(57) **CLAIM**

The ornamental design for a makeup brush cleaning box, as shown and described.

DESCRIPTION

FIG. 1 is a top perspective view of a makeup brush cleaning box, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a bottom perspective view of the makeup brush cleaning box, shown in an environment of use.

The broken lines in the drawings illustrate the portions of the makeup brush cleaning box, which form no part of the claimed design.
